JOHN PRIMROSE, OF DONGAN HILLS, NEW YORK, ASSIGNOR TO POWER SPECIALTY COMPANY, OF NEW YORK, N. Y., A CORPORATION OF NEW YORK.

OIL STILL.

Application filed December 28, 1920. Serial No. 433,588.

In the specification which follows, it is my aim to set forth and my desire to define the novel features of an oil still which I have devised and which I have been led to design 5 to overcome certain difficulties heretofore met with in devices of this character. The invention resides in what is known as a cracking still, and the improvements which I have made and illustrated herein are designed to 10 accomplish the following, amongst other, useful objects.

First, a better and more even distribution of the hot gases over the entire area of the furnace or heating chamber containing the 15 oil pipes and an improved means of regulating the temperature and securing a more complete combustion of the fuel.

Second, a more effective flow of the oil to be treated through the system of pipes, 20 whereby the same temperature in the oil in all the pipes may be secured.

Third, a more ready means for inspecting the tubes or pipes for the purpose of detecting weak spots.

25 Fourth, a more convenient and ready means of withdrawing an injured or impaired tube section for replacement by a new section, and

Fifth, certain minor details of construction which contribute to the efficiency and 30 general practical value of the still.

In the annexed drawings in which the means for accomplishing the above stated objects are shown:

35 Fig. 1 is a vertical section of the entire device.

Fig. 2 is a vertical section of the same on line 2—2 of Fig. 1.

Fig. 3 is a horizontal section of the same 40 on line 3—3 of Fig. 1, and

Figs. 4 and 5 are detail views of the pipe sections, showing the same in different positions.

Fig. 6 shows an enlarged detail view of 45 the tubes with casings of varying outer surfaces.

Referring to Fig. 1: The structure shown is, in the main, of the usual construction and built up of proper materials with a furnace 50 or combustion chamber 1 in front, a bridge wall 2, and a bank of oil pipes arranged back of the same. The hot gases from the fire pass up over the wall 2, down through the bank of tubes or pipes and off to the flue through 55 an opening 3 controlled by a damper 4.

Usually in devices of this kind a regulable volume of cold or relatively cool air is introduced into the combustion chamber above the flame or fire, and is assumed to mix with the hot gases and pass over the oil pipes. It 60 has been found, however, that the distribution of the cooler air is seldom, if ever, uniform, and that the gases contain strata or zones of higher and lower temperature, resulting in an uneven heating of the oil in the 65 pipes with which the gas comes in contact. To avoid this I introduce a large volume or excess of cool air up through the bottom of the furnace, preferably through a checkered partition or grate 5, beneath which is a chamber 6 with the proper number of controllable dampers 7, 8, in front, on the side or both.

The source of heat may be an oil flame or a coal fire on a stationary plate or stoker. Of course if the latter be used the air passages through the grate or stoker should be 70 greatly increased in area which would be the equivalent of supplying a very large grate area and will result in a low burning rate per square foot of grate. In either event the 75 air promotes and secures a more perfect combustion, is mixed thoroughly and uniformly with the hot gases, and the temperature of the mixture as it passes over the wall 2 and impinges upon the oil pipes may be 80 closely regulated at all times by the adjustment of the dampers and the amount of fuel supplied.

The oil pipes 9 are arranged in sections or groups none of which contains more than 90 two horizontal rows of pipes, and all of which groups are separated by a given space. The chamber containing the pipes is provided with parallel openings or sight holes 10 extending vertically over the entire bank of 95 tubes, and these are normally closed by doors 11, which may at any time be removed to exhibit the pipes within. By this means the pipes may, at any time, be examined, and if any pipe is seen to have developed a hot 100 spot, the apparatus is at once shut down and the impaired pipe section removed and replaced by a new section. As a space is left between each row or two rows, all of the surfaces may be thus inspected and weak spots 105 immediately detected.

The pipe sections are connected in multiple series, as indicated in the drawing, Fig. 2. That is to say, all the pipes in each vertical staggered row are in series, while all of 110

the series connect with the upper and lower manifolds 12, 13. The oil is introduced at the bottom and passes upward thus securing a perfect flow counter to that of the hot gases which pass downward.

The oil pipes, as shown in Figs. 4 and 5 are encased in corrugated cast iron envelopes and the thickness of these envelopes varies with the temperature of the gases to which 10 the pipes are exposed. It is difficult to clearly illustrate this, but an examination of Fig. 1 and Fig. 6, particularly of the pipes in the third group from the top in Fig. 1, will show that the casings 25 on the pipes 15 on each side of the upper row are shown larger than those between which are marked 26 in Fig. 6. This plan may be followed in the whole or in any part of the row or rows near the top, but is particularly desirable 20 in the rows nearest the top, the central tubes in which are of smaller outside diameter because the flow of gases is naturally down the center to a greater extent than down the sides of the bank. The greater the diameter 25 of the envelopes, the greater the extent of the heat absorbing surface exposed to the gases, so that a pipe with a thick envelope will absorb as much heat in a region of lower temperature, as a pipe with a thin envelope 30 in a region of higher temperature.

The purpose in so modifying the thickness of the iron envelopes is to secure an even temperature in the oil as it issues from the pipes. Observation or experiment will readily 35 determine this and indicate the proper thickness for the pipes in different parts of the bank. To assist in such determination each vertical series of pipes is provided with a thermometer 14, Fig. 2, at a 40 point just before it delivers into the outlet manifold, and further provision for regulation of temperature may be had by the use of valves 15 in the pipes beyond the inlet manifold, as indicated in Fig. 3, by the 45 adjustment of which the flow of oil through certain series of pipes in which the oil is too little heated may be throttled and reduced, thereby increasing the rate of flow through the others in which the temperature 50 is higher. This is an important consideration.

As stated above, when an impaired or defective pipe section is detected the device should be shut down and that section removed. The means which I have provided for this operation is shown in Figs. 2, 4 and 55 5 and reference will now be had to said figures.

The ends of each pipe section are provided 60 with rectangular cast iron flanges 16 against which the corrugated envelopes abut. The lower pipe sections of each group rest upon I-beams 17, in the setting, so that the upper sections are firmly supported by the flanges 65 16. The side wall of the heating or pipe

chamber on one side is built up around these beams by solid blocks or bricks of refractory material 18, which contain recesses to receive the lower flanges of the I-beams, and by a packing or filling 19 of suitable material applied by tools after the pipes are in place. The blocks or bricks 18 fill the spaces between the lower flanges of the under row of pipes in each group and the upper flanges of the top row of the next group of pipes 75 below.

On the other side of the chamber these spaces between groups are filled with two bricks or blocks 20 and 21, the under brick 21 having a recess which admits the flange 80 on the pipe and extends down to the upper pipes of the row beneath. In this case the upper brick 20 is held in place between the flange of an I-beam and the flange on the pipe resting upon said beam.

Should a pipe or pipe section be found by inspection to have developed a hot or weak spot, the apparatus is shut down and the filling 19 on both sides of the group or pair of pipe sections in which the defect occurs 90 and on the right, as shown in Fig. 5, is knocked out and the refractory block 18 pushed in or away from the I-beam, as shown in said figure. The filling or packing 19 on the other side is also knocked out on each 95 side of the group, and the lower brick 21 withdrawn. This permits the group or pair of pipe sections to be raised as the other pipes are supported in place by the I-beams, so that when the ends of these sections are 100 cut off from the headers at the right, Fig. 5, the group of two sections may be withdrawn and replaced by new or perfect sections.

After such new sections are inserted the 105 walls of the chamber may be restored to their original condition with little labor and expense, after the ends of such sections have been expanded into the headers.

The device in other respects than those 110 herein particularly set forth is or may be of the usual construction employed in the art, and requires no more detailed description. The distillation of oil has reached a stage at the present time where the highest plant efficiency of the still, the most precise observance of proper operating conditions and perfect control of all factors is demanded. This implies that changes in construction 115 which are seemingly slight may be of the utmost commercial value and importance. The several features which are hereinbefore described are in certain respects refinements in this class, and their importance can best be estimated by a comparison of results. 120 The apparatus which I have described has been demonstrated to possess these advantages to a very marked degree.

What I claim is:

1. In an oil still of the kind described, the 130

- combination with a fire chamber having a checkered bottom, a combustion zone disposed at a point, spaced from and above said bottom, means for forcing air through said bottom to reduce the temperature of the hot gases of combustion after combustion has taken place, said bottom serving to uniformly distribute said air in said products of combustion, a bridge wall, and a bank of oil pipes placed back of the bridge wall over which pipes the hot gases of combustion and the introduced and uniformly mixed air flow downward and counter to the current of oil passing through the pipes, said bridge wall and supplementary air cooperating to prevent overheating of the oil passing through said pipes.
2. In an oil still comprising a fire chamber and a heating chamber, said heating chamber receiving hot gases from the fire chamber, a bank of tubes in the heating chamber, each tube having a cast iron envelope, the outside surfaces of the different tubes at various locations varying inversely as the temperature of the gases impinging thereon,
- said tubes adjacent the walls of the heating chamber at points of low gas velocity also having said casings with a greater surface thereon than on the casings on certain of the tubes nearer the center of said chamber at points of relatively higher gas velocity.
3. In an oil still comprising a fire chamber and a heating chamber which receive hot gases from the fire chamber, of a bank of horizontal tubes in the heating chamber, each tube having a cast iron envelope, the outer surfaces of the various tubes varying in an inverse proportion to the temperature of the gases impinging thereon, certain envelopes upon certain of the tubes of the row initially receiving the hottest gases having reduced heat absorbing surfaces at points of relatively high gas velocity across a row and with increased surfaces upon the tubes of such row at points of relatively lower gas velocity.

In testimony whereof I hereto affix my signature.

JOHN PRIMROSE.
